MOTOR CONNECTION

Filed Sept. 12, 1929

FIG. 1.

FIG. 2.

UNITED STATES PATENT OFFICE

CHARLES S. BAKER, OF CORNING, NEW YORK, ASSIGNOR TO INGERSOLL-RAND COMPANY, OF JERSEY CITY, NEW JERSEY, A CORPORATION OF NEW JERSEY

MOTOR CONNECTION

Application filed September 12, 1929. Serial No. 392,151.

This invention relates to motor connections, but more particularly to a connection adapted to support a motor in operative relationship with an element intended to be driven, as for instance, the cable drum of a coal cutting machine.

One object of the invention is to assure against the chafing of a cable wound on a drum to which the motor may be attached.

Other objects will be in part obvious and in part pointed out hereinafter.

In the drawing illustrating the invention and in which similar reference characters refer to similar parts,

Figure 1 is a plan view of a coal cutting machine with its cable drum having the invention applied thereto, and

Figure 2 is an elevation, partly in section, of the invention illustrating in detail the manner in which it supports the cable drum and the motor.

Referring to the drawing, and at first more particularly to Figure 1, A represents a coal cutter having a cutter bar B for guiding a chain C carrying cutting picks D for cutting a kerf E in the coal F.

The coal cutter A illustrated may be of the type adapted to be operated electrically, and the motor (not shown) for operating the chain C and also for bodily actuating the cutter A relatively to the work may be housed in a casing G of the coal cutter.

On the casing G may be mounted a turn-table H having a central aperture J to accommodate a trunnion K mounted on the casing G to form a pivot for the turn-table H.

The parts so far described may be of well known types as may also be a cable drum L intended to be supported by the turn-table H and carrying a cable O leading from a source of electrical energy supply to the motor or motors whereby the coal cutter is actuated.

Preferably the drum L is mounted on a hollow shaft P to which it may be fixedly secured in any suitable manner by a key Q.

In accordance with the present invention, one end of the drum L is supported by a member R which has a recess S to receive an extension T of the drum L, and near the

outer end of the recess S may be formed grooves U for packing members V which encircle the extension T to prevent the entrance of dust along the cooperating surfaces of the extension and the recess. In order to reduce friction between the wall of the recess S and the extension T to a minimum the shaft P is seated in a frictionless bearing W disposed in the recess S.

Secured to the outer end of the member R in any suitable and convenient manner, as for instance, by means of bolts X is a rotary pneumatic motor Y having a gear train Z which extends into a recess b of the member R so that the member R in effect also serves as a gear casing for the motor Y. The pressure fluid for actuating the motor Y may be conveyed thereto from a source of supply by a connection Y'.

The motor Y may be of the small portable type commonly employed for threading nuts on bolts and similar work. The driven gear c of the motor therefore has a socket d for the reception of a working implement such as a drill or wrench, which motors of this type are adapted to accommodate. In the present instance, instead of a working implement, a shaft e is inserted in the socket d and is journaled in a bushing f inserted in a wall g which divides the recess b from the recess S and serves as an abutment for shoulders 2 and 3 on the shafts P and e respectively which act against opposite sides of the wall. The free end of the shaft e may be provided with grooves h to interlockingly engage inverted ribs j in the end of the drum shaft P.

Preferably formed integrally with the member R is a standard k having a base o which is seated on the turntable H and secured thereto in this instance by means of bolts p.

In practice, the motor Y may be disposed on the side of the member R and the shaft e entered into splined engagement with the shaft P. The motor Y may then be secured to the member by means of the bolts X.

During the operation of the coal cutter, the motor may be opened to communication with a pressure fluid supply through the connec-

tion Y' so that the motor will constantly tend to rotate in a direction for winding the cable O on the drum L in accordance with the movement of the coal cutter A relatively to the work. By using a motor capable of delivering only comparatively low power, the cable may be constantly wound tightly on the drum L with the consumption of only a minimum amount of pressure fluid for driving the motor.

- 10 Whenever the coal cutter A is being moved in a direction in which it becomes necessary to unwind a portion of the cable from the drum L, it will not be necessary for the motor to be first reversed since the resistance which it exerts on the drum L tending to wind the cable thereon may be readily overcome so that the motor may then be run in a reverse direction by the cable O. Irrespective of the direction in which the coal cutter may move the motor will at all times assure against the contact of the cable with the rough surfaces of the floor whereby the cutting apparatus is supported, and consequently the cable O will be protected against chafing. This is highly essential, particularly when used in coal mining operations in which destructive explosions frequently occur due to the formation of a spark by a peeled cable coming in contact with other metallic substances.

30 I claim:

35 In a motor connection, the combination of a member and a standard for supporting the member, recesses in the ends of the member, a wall between the recesses and having a bore, a driven member journaled in one recess and having a shoulder seating against the wall, a motor secured to the member and having a gear train extending into the other recess, a shaft driven by the gear train journalled in the bore and slidably interlocking with the driven member, and a shoulder on the shaft acting against the wall to limit movement of the shaft in the direction of the driven member.

40 45 In testimony whereof I have signed this specification.

CHARLES S. BAKER.
